CLAIM

The ornamental design for a backpack with cooler, as shown and described.

DESCRIPTION

FIG. 1 is a front elevational view of the backpack with cooler, shown in an exploded condition;

FIG. 2 is a back elevational view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a top, front, left side perspective view thereof.

The cross-hatched pattern shading shown on the drawings represents a textured, fabric surface.
